UNITED STATES PATENT OFFICE.

FRANK A. PESCHL, OF JACKSON HEIGHTS, NEW YORK, ASSIGNOR TO INTERNATIONAL PAPER COMPANY, A CORPORATION OF NEW YORK.

MOISTURE-TESTING MEANS FOR PAPER-MAKING MACHINES.

Application filed June 22, 1926. Serial No. 117,662.

This invention relates to paper making machines, and has reference more particularly to means cooperative with the traveling moist paper web, to indicate the moisture content of the same. Knowledge, available at any time, of the amount of moisture content in the web at any given point, is very desirable and important, since it discloses to the attendant or those in charge of the operation of the paper making machine, the condition of operation of the presses, the felts, the suction apparatus, etc. It shows if the presses are unevenly or otherwise improperly weighted, or if the felts are still high in their water removing qualities, as they should be. It shows also how much moisture enters the driers, and indicates various other conditions of operation, the knowledge of which makes it possible to effect economy in the operation of the machine and the maximum capacity in production.

The present invention is based on the resistance which a paper web offers to the flow therethrough of a current of electricity, which flow will be directly proportional to the moisture content of the web; and in accordance with the present invention, advantage is taken of this fact by the provision of a contactor member or shoe of improved form and construction, which is provided with spaced contact plates or surfaces adapted to rest on and contact with the traveling moist paper web, and which contact surfaces are connected in an electric circuit supplied with a suitable electric current, the said circuit including an electric-current indicating instrument for indicating the amount of current passing. The electric current will flow from one contact surface of the contactor shoe to the other surface through the portion of the paper web bridging said contact surfaces, and according to the condition of the web, as regards its moisture content, it will offer a greater or less resistance to said flow, and the amount of current passing will be indicated by the indicating instrument, the greater the moisture content the greater the current flow, and vice versa. Also in accordance with the invention, means are provided, cooperative with the electric current being measured, for compensating for differences and variations in the acidity of the paper stock, so that notwithstanding such variations in acidity,

which frequently occur in the operation of paper making machines, a true and accurate indication of the moisture content will be given.

The form and arrangement of the parts 60 of the mechanism embodying the above described characteristics, will be described in detail in the specification to follow, and the novel features thereof will be pointed out in the appended claims.

In the accompanying drawings:

Fig. 1 is a side elevation, diagrammatic in character, of a Fourdrinier paper making machine showing my invention applied thereto.

Fig. 2 is a perspective view, on an enlarged scale, of the third press roll, the baby drier cylinder, and the first two main drier cylinders, and showing the contactor shoe applied to cooperate with the stretch of the 75 paper web in its passage from the press rolls to the baby drier.

Fig. 3 is a sectional view of the contactor shoe and a portion of the paper web, showing diagrammatically the passage of the electric current from one contact surface to the other, through the intervening portion of the web.

Fig. 4 is a front elevation, on an enlarged scale, of the contactor shoe and its support, 85 certain parts being broken away to better show the construction.

Fig. 5 is a vertical sectional elevation through the lower portion of Fig. 4.

Fig. 6 is a plan view of the contactor shoe.

Fig. 7 is a diagrammatic view of one form of means for the automatic compensation of variations in acidity of the paper stock.

Fig. 8 is a similar view of a form of acidity compensating means in which the 95 compensation setting is effected manually.

Fig. 9 is a similar view of a different form of manually operated compensating means.

Referring to the drawings:

Referring to Figs. 1 to 6, the paper making machine there shown comprises the usual flow box 1, the forming wire 2 in position to receive the paper stock or pulp from the flow box, the three presses 3, 4 and 5, the baby drier cylinder 6, and the main drier 105 cylinder 7.

8 designates the contactor shoe, shown as resting on the stretch 9 of paper web where it passes from the third press 5 to the baby drier cylinder 6, this being the point in the 110

machine where I prefer to locate the shoe for the application of the testing current. It may however be located at other parts of the machine and wherever the moisture content of the paper web is such as to permit a sufficient flow of electric current to actuate an electric-current indicating instrument.

The contactor shoe is furnished with spaced metal contactor plates 8^a and 8^b insulated from each other and exposed on the under face of the shoe, so that with the shoe resting on the paper web, these plates will contact therewith. The contact plates have connected with them, electric conductors 10 and 11 respectively, constituting an electric circuit which is supplied with an electric current from a suitable source A indicated diagrammatically in Fig. 1, said circuit having connected in it an electric-current indicating instrument B such for instance as a galvanometer, ampere-meter, milliampere-meter, or the like. The instrument in the form shown, is provided with a pointer b' actuated electrically by a coil b connected in the circuit constituted by the conductors 10 and 11.

In the operation of the device, the insulated contactor plates will maintain electric contact with the traveling moist paper web, and the electric current will flow from one contact plate to the other and through the intervening section of the web, and the amount of current passing will be indicated by the indicating instrument, the latter showing a greater or less flow of current according to the moisture content of the web, the greater the moisture content, the greater the flow of current, and vice versa.

The detailed construction and form of the contactor shoe and manner of supporting the same in the machine is best shown in Figs. 4, 5 and 6, and will now be described. The contactor shoe is in the form of a block or body 12 formed of some insulating material such as bakelite or other suitable composition or material. The block is elongated in the direction of travel of the paper web and is curved on its under surface, which presents a flat central portion 13, and upwardly curved end portions 14, the purpose of which will presently appear. The contactor plates 8^a and 8^b before alluded to are set in the flat portion of the block and are arranged side by side parallel to each other with spaces 15 between adjacent plates, there being in the present instance two plates 8^a and three plates 8^b , alternating with each other. These plates are formed of some metal of good electric conducting quality such as copper, and their under surfaces are exposed on the under surface of the block so as to contact electrically with the surface of the paper web. The plates are fastened firmly in the block by means of fastening screws 16 extending downwardly through the block and engaged at their ends with the respective plates at op-

posite ends of the same. The plates 8^a are electrically connected together by a metallic connecting strip 18 attached to the bolts 16 at one end of the plates; and the plates 8^b are similarly connected together electrically by a metallic connecting strip 17 attached to the bolts 16 at the opposite ends of the plates 8^b as best shown in Fig. 6, the electric conductor 10 being connected with the connecting strip 18, and the conductor 11 with the other strip, so as to connect the two series of contact plates in the electric circuit including the measuring instrument B.

The contactor block 12 is supported in the machine, as will be more fully described later, so as to rest with a floating action on the traveling web, pressing the same down gently in a slightly curved form, which action is permitted by the curved end portions of the block as above referred to; and in such floating action of the block, the degree of pressure on the web will not vary the area of contact therewith of the contactor plates, since said plates are confined to the central flat portion of the spoke, and without regard to the degree of pressure of the block, the plates will always contact throughout their entire extent with the web. This insures a reliable and uniform action of the parts, and avoids the necessity of observing any particular accuracy or nicety in the setting of the contactor for operation.

The floating action of the contactor shoe referred to, is secured by connecting the same to an overhead support 19 by means of a transverse pivot bolt 20 which is extended through a bracket 21 fixed at its ends to the ends of the block, and through ears 22 depending from said overhead support, whereby the block may rock vertically relatively to said support about a transverse axis disposed centrally of the block, said rocking motion being in a plane disposed in the direction of travel of the paper web. The overhead support 19 is provided with laterally extending arms 23 connected to and projecting in opposite directions from, the depending ears 22, from which arms extend upwardly, two fixed vertical guiding rods 24 extending loosely through guiding openings in a clamping plate 25. The plate 25 is clamped to the upper sides of two parallel spaced supporting bars 26 extending transversely across the machine between the press roll 5 and baby drier, which bars are fixed at their ends to the rear ends of bracket arms 27 which extend forwardly and are connected at their ends to a transverse beam 28 fixed to the upper ends of standards 29 disposed at the sides of the machine, all as shown in Fig. 2.

The plate 25 is so clamped to the supporting bars 26 as to permit of the lateral adjustment of the contactor shoe along the supporting bars to different positions in the

width of the paper web, so that the moisture content at any point in the web may be determined and thus an average for the entire lateral extent of the web arrived at. The 5 clamping of the plate to bring about this object is effected in the present instance by means of a clamping frame 30 applied to the undersides of the supporting bars, from the ends of which frame, clamping bolts 31 extend upwardly, between the supporting bars and through the ends of the clamping plate and have clamping nuts 32 screwed on their upper ends, which nuts when screwed up will engage the upper side of the clamping 10 plate.

In effecting the adjustment of the contactor shoe laterally of the paper web as above referred to, I prefer to employ a horizontal adjusting screw 33 mounted for rotation 20 in bearings in the rear ends of the arms 27, which screw is engaged in a threaded hole in a lug 34 extending rearwardly from the clamping plate 25, the said screw being provided with a crank 35 for turning it. It 25 will be understood that in adjusting the contactor shoe laterally by the screw 33, the clamping plate 25 will first be released by unscrewing the nuts 32, which, after the adjustment has been made, will again be 30 tightened up to hold the parts in their adjusted position.

The overhead support 19 is so connected with the clamping plate that the support and consequently the contactor shoe may be 35 adjusted vertically, and this in order to vary the degree of pressure of the shoe on the paper web to meet the conditions encountered in the practical operation of the machine. This adjustment is effected in the 40 present instance by means of a vertical adjusting screw 36 engaged in a central threaded hole in the clamping plate and swiveled at its lower end as at 36^a in the overhead support 19, the said screw having 45 a hand wheel 37 fixed to its upper end for turning it in effecting the adjustments. A lock nut 38 is applied to the screw and is adapted, when screwed up, to bind against the upper side of the clamping plate and 50 thereby lock the screw in its adjusted position. It will be understood from the construction described that by turning the adjusting screw, the contactor shoe may be moved up and down to different positions, 55 the guiding rods 24 in such adjustments sliding through the guiding openings in the clamping plate and thereby guiding and steadyng the parts in their adjusting movements.

60 The electric conductor 10 is connected to one end of the connecting strip 18 by a binding nut 39 applied to the upper extended end of the fastening screw 16 at that end of the strip, whereby the contact plates 8^a are connected in the electric circuit; and the con-

ductor 11 is connected to one end of the contact strip 18 by a binding nut 40 applied to the upper extended end of the fastening screw 16 at that end of the strip, thereby connecting contact plates 8^b in said circuit, 70 so that with the contactor shoe in operative position and with the contact plates 8^a and 8^b in engagement with the traveling paper web, the circuit will flow through and between the adjacent plates and the portions of the web bridging the spaces between the plates, and the amount of the current flow, controlled and determined by the degree of moisture in the web, will be indicated by the instrument B included in said circuit as 75 hereinbefore described.

It will be understood from the foregoing description that the testing current does not traverse any metal part of the machine or machine frame, as it is not grounded through 80 the machine, but passes directly from one contact plate of the contactor shoe to the other, and therefore is entirely independent of the parts of the machine itself. And it is only necessary that it be held against the 85 paper web to perform its functions, and is preferably supported as shown so as to be freely floating.

The surfaces of the contact plates, due to 90 the sweep of the traveling web thereover, are kept clean and free from dirt or foreign matters. Consequently the current will flow uniformly and without interruption, and a reliable indication of the same by the indicating instrument will be secured.

100 The peculiar design of the contactor shoe as described, exposes to the paper web, a definite surface of contact of the contactor plates, and the lower surface of the shoe is, as before explained, so shaped as to press the 105 web down in a slight depression or curve, and without regard to the degree of pressure of the shoe on the paper web, the area of contact of the plates in engagement with the web will always be the same. As the 110 paper web is thin in cross section, it can pass only a certain amount of current, and therefore it is evident that it is not necessary for the contact shoe to press down very hard upon the web in order to cause the current 115 to pass therethrough.

120 The instrument for indicating the current, will be preferably calibrated in percent moisture, and may be of the direct reading and recording type, and in the form of a galvanometer, ampere-meter, milliamperemeter, or other suitable form of instrument for indicating the passage of an electric current.

125 As the contactor shoe can be moved across the machine as hereinbefore described, the moisture content in any part of the sheet may be determined, and the average throughout the lateral extent of the sheet arrived at. Or this average may be determined by 130

a series of contactors fixed at different points in the width of the sheet; or groups of contactors can be made up extending partially or entirely across the machine.

5 It frequently happens, in the operation of paper making machines, that the acidity of the stock fed to the forming wire and going to make up the paper web, will vary, and in order to prevent such variations in 10 acidity from causing a false indication by the measuring instrument of the moisture content, I have devised different forms of compensating devices to meet this condition, which are illustrated diagrammatically in 15 Figs. 1, 7, 8 and 9, and will now be described.

On reference to Fig. 1 it will be seen that there is provided a small tank or vessel 42, in which circulates the paper stock from 20 the flow box 1, through pipes 43 and 44. Immersed in the stock in this tank are two electrode plates 45 and 46. An electric conductor 47 is connected at one end with the electrode plate 45, and is connected at its 25 other end to the conductor 11 at a point beyond the instrument B; and an electric conductor 48 is connected at one end to the electrode plate 46, and at its other end to the conductor 11 on the other side of the 30 instrument B, and between it and the contactor shoe, these conductors thus constituting a branch circuit of the main circuit constituted by conductors 10 and 11. By this arrangement the increased flow of the current, due to the acid condition of the stock, is prevented from acting on the instrument 35 B and causing said instrument to indicate a higher percentage of moisture in the web than actually exists, the excess current being diverted by conductors 48 and 47 through the tank 42 and around the instrument, so as not to pass through and act on the same. In this manner, whatever excess 40 flow there is of the current due to variations in acidity, is prevented from acting on the indicating instrument, and the latter will therefore indicate the true moisture content without regard to the degree of acidity existing.

45 In Fig. 7 is illustrated another form of compensating device. In this case the arrangement is the same as that just described, except that the conductor 47^a instead of being shunted around the instrument, is connected with a coil 49 incorporated in the instrument and wound in a direction opposite that of the actuating coil b of the instrument, so as to oppose the action of the coil b in operating the needle or pointer b'. 50 In this case the excess of current instead of being shunted around the instrument as in that first described, is caused to act on the instrument with a compensating effect.

55 In a further modified arrangement of compensating device shown in Fig. 8, the tank

42 of Fig. 1 is entirely omitted, and for it is substituted a resistance 51 connected at one end with the conductor 47^b. A lever switch 52 is connected with the conductor 48^b so that more or less resistance can be thrown in 70 the circuit according to the increase of acidity in the stock. This device requires for its setting, a pre-knowledge of the amount of acidity existing.

The arrangement shown in Fig. 9 illustrating still another form, is based on the principle of operation of that shown in Fig. 8, i. e., a resistance regulated by hand is thrown in the circuit and the amount of resistance determined by a pre-knowledge of the degree 80 of acidity existing. In this case however the resistance is connected in series in the circuit, a conductor 53 leading directly from the contactor shoe to the switch lever 52^a, and a conductor 47^c leading directly from 85 the resistance 51^a to the coil of the instrument B^a.

In all of the different forms of compensating devices or arrangements described, means are provided whereby the increased flow of 90 the current, due to increase in acidity, is prevented from acting on the measuring instrument to cause it to indicate a false moisture content, which would otherwise be indicated by reason of the action of the increased flow 95 of current on said instrument.

In the foregoing description and accompanying drawings, I have set forth my invention in the particular detailed form which I prefer to adopt. It will be understood 100 however that these details may be variously changed and modified, without departing from the limits of the invention; and that the invention is not limited to any particular form or construction of the parts, except in 105 so far as such limitations are expressed in the claims.

Having thus described my invention, what I claim is:

1. In a paper making machine, the combination of means for supporting the traveling paper web, a contactor member provided with spaced contact surfaces insulated from each other, means for supporting said member in fixed relation to the travel of the web 115 and with said surfaces in contact therewith, whereby the web in its travel will sweep over said surfaces and keep them clean, an electric circuit including said contact surfaces, and an electric-current indicating instrument included in said circuit.

2. In a paper making machine, the combination of means for supporting the traveling paper web, a contactor member provided with spaced contact surfaces insulated from each other, means for supporting said member with the surfaces in contact with the paper web and spaced transversely of its path of travel, an electric circuit including 125 said contact surfaces, and an electric-current 130 indicating instrument.

- indicating instrument included in said circuit.
3. In a paper making machine, the combination of means for supporting the traveling paper web, a contactor member provided with spaced contact plates insulated from each other, means for supporting said member in fixed relation to the travel of the paper web and with the plates in contact with the web and parallel with its line of travel, an electric circuit including said contact plates, and an electric-current indicating instrument included in said circuit. 70
4. In a paper making machine, the combination of means for supporting the traveling paper web, a contactor member provided with spaced contact surfaces insulated from each other, and means for giving floating support to said member on the paper web, with the said surfaces in contact therewith, an electric circuit including said contact surfaces, an electric-current indicating instrument included in said circuit. 75
5. In a paper making machine, the combination of means for supporting the traveling paper web, a contactor member provided with spaced contact surfaces insulated from each other, means for supporting said contactor for rocking motion over the traveling paper web, with said surfaces in contact therewith, an electric circuit including said contact surfaces, and an electric-current indicating instrument included in said circuit. 80
6. In a paper making machine, the combination of means for supporting the traveling paper web, a contactor member provided with spaced contact surfaces insulated from each other, means for supporting said contactor to rock vertically about a horizontal axis extending transversely of the direction of travel of the paper web, with said contact surfaces in contact with said web, an electric circuit including said contact surfaces, and an electric-current indicating instrument included in said circuit. 85
7. In a paper making machine, the combination of means for supporting the traveling paper web, a contactor member comprising a supporting block and a plurality of contact plates carried thereby in spaced insulated relations and exposed on the underside of the same, means for supporting the block over the traveling paper web with the exposed surfaces of the plates in contact with said web, an electric circuit including said contact plates, and an electric-current indicating instrument included in said circuit. 90
8. In a paper making machine, the combination of means for supporting the traveling paper web, a contactor member comprising a supporting block having its under surface flat at the central portion and curved at its ends upwardly to ride on the paper web, and contact plates set in said block in spaced insulated relations with their under surfaces exposed at the central flat portion of the block, means for supporting the block over the paper web with the plates in contact therewith, an electric circuit including said plates, and an electric-current indicating instrument included in said circuit. 95
9. In a paper making machine, the combination of means for supporting the traveling paper web, a contactor member comprising a supporting block, a plurality of spaced contact plates set therein and insulated from each other and exposed on the underside of the block, said plates being electrically connected together in two series, with the plates of one series alternating with those of the other series, means for supporting the block over the paper web with the plates in contact therewith, an electric circuit including said two series of plates, and an electric-current indicating instrument included in said circuit. 100
10. In a paper making machine, the combination of means for supporting the traveling paper web, a contactor member provided with spaced contact surfaces insulated from each other, means for supporting said member over the paper web, with said surfaces in contact therewith, means for adjusting said contactor member vertically relative to the paper web, an electric circuit including said contact surfaces, and an electric-current indicating instrument included in said circuit. 105
11. In a paper making machine, the combination of means for supporting the traveling paper web, a contactor member provided with spaced contact plates insulated from each other, a support for said contactor member adjustable transversely of the paper web, means for adjusting said member vertically in its support to and from the paper web, an electric circuit including said contact plates, and an electric-current indicating instrument included in said circuit. 110
12. In a paper making machine, the combination of means for supporting the traveling paper web, a fixed guide extending horizontally above and across the web, a contactor member adjustable on said guide and provided with contact surfaces adapted to contact with the traveling web, means engaging the contactor to adjust the same on its guide, an electric circuit including said contact surfaces, and an electric-current indicating instrument included in said circuit. 115
13. In a paper making machine, the combination of means for supporting the traveling paper web, and means for indicating the moisture content of the paper web, said indicating means being applied to act on the stretch of the paper web at a point where said strip bridges the space between the last press and the baby drier. 120
14. In a paper making machine, the com- 125
15. In a paper making machine, the combination of means for supporting the traveling paper web, a contactor member provided with spaced contact surfaces insulated from each other, means for supporting said member over the paper web, with said surfaces in contact therewith, means for adjusting said contactor member vertically relative to the paper web, an electric circuit including said contact surfaces, and an electric-current indicating instrument included in said circuit. 130

bination of means for supporting the traveling paper web, and means independent of the web supporting means for indicating the moisture content of the paper web, said indicating means being applied to act on the upper side of a stretch of the paper web between two spaced supporting points.

15. In a paper making machine, the combination of means for supporting the traveling paper web, electrically operated means cooperating with the web for indicating the moisture content thereof, and electrically actuated compensating means for said indicating means operating automatically in association with the indicating means to prevent variations in acidity of the stock from causing a false indication.

16. In a paper making machine, the combination of means for supporting the traveling paper web, a member provided with contact plates to contact with the paper web, an electric circuit including said plates to pass a current of electricity through the web, an electric-current indicating instrument included in said circuit, an electric circuit branching from said first mentioned circuit and operating automatically in association with the indicating means to prevent variations in acidity of the stock from causing a false indication, and means whereby the resistance in said branch circuit may be varied in accordance with variations in the acidity of the paper stock.

17. In a paper making machine, the combination of means for supporting the traveling paper web, a member provided with contact plates to contact with the paper web, an electric circuit including said plates to pass an electric current through the web, an electric-current indicating instrument included in said circuit, and an electric circuit branching from said first mentioned circuit and operating automatically in association with the indicating instrument for compensating the action of the same according to variations of acidity in the stock, said branch circuit passing through a body of the paper stock making up the web.

18. In a paper making machine, the combination of a flow box to contain a supply of the paper stock, means for supporting the traveling paper web, a member provided with contact plates to contact with said web, an electric circuit including said plates to pass an electric circuit through the web, an electric-current indicating instrument included in said circuit, a tank in communication with the flow box and supplied with paper stock therefrom, electrodes immersed in the stock in said tank, and an electric circuit branching from the first mentioned circuit and including said electrodes.

In testimony whereof, I have affixed my signature hereto.

FRANK A. PESCHL.
